UNITED STATES PATENT OFFICE.

VINCEN P. McVOY, OF MOBILE, ALABAMA, ASSIGNOR TO UNITED STATES RAILWAY SUPPLY COMPANY, OF DOVER, DELAWARE, A CORPORATION OF DELAWARE.

DRIFTING VALVE.

1,403,129.

Specification of Letters Patent. Patented Jan. 10, 1922.

Application filed March 30, 1920. Serial No. 369,880.

To all whom it may concern:

Be it known that I, VINCEN P. McVoy, a citizen of the United States, residing at Mobile, in the county of Mobile and State 5 of Alabama, have invented certain new and useful Improvements in Drifting Valves, of which the following is a specification.

This invention relates to certain new and useful improvements in what are known as 10 "drifting" valves for locomotives and while the present invention is along the same general line as prior devices of this nature devised by me, one of which, for instance, may be seen in Patent No. 1,229,993, dated 15 June 12, 1917, it is to be understood that the novel features hereinafter disclosed and claimed are not necessarily confined to their association with the details of construction in other respects disclosed in said patent, 20 but are applicable to other forms of drifting valves with which they may be associated.

The present invention has for its objects among others to provide an improved drifting valve of the general character disclosed 25 in my said patent whereby the valve itself, is provided with means for creating a vacuum.

The present invention has for a further 30 object to provide simplified means for accomplishing this object.

This can be accomplished in a variety of ways, some of which I have herein illustrated, but it is to be understood that the 35 invention in its broad sense is in no wise restricted to such particular forms of construction.

Other objects and advantages of the invention will hereinafter appear, and the novel 40 features thereof will be particularly pointed out in the appended claims.

The invention, in such forms as at the present time appear to be the preferable ones, is clearly illustrated in the accompanying drawings, which, with the numerals of reference thereon, form a part of this 45 specification, and in which—

Figure 1 is a substantially central vertical section through my improved valve.

Figure 2 is a similar view showing a 50 slightly modified form.

Figure 3 is a view similar to Figure 1, showing the relation of the parts when the valve is open.

Like numerals of reference indicate like 55 parts throughout the different views.

Referring to the drawings, 1 designates the body portion of the valve, 2 the cap or head thereof secured in position in any suitable way.

60 3 is a lower portion preferably substantially cone-shaped, as shown, with a depending cylindrical portion 3a.

The body portion has upon diametrically opposite sides extensions 1a, 1b, for suitable 65 connection with the union members 4 and 4a, respectively, the former designed for connection with the boiler and the latter for connection with the engine. Any suitable form of union connection may be employed.

70 5 is a steam piston fitted to reciprocate within the upper cylindrical portion of the body 1 of the valve, having suitable packing rings, as shown. The said piston is provided between its upper and lower faces 75 with an annular space or channel 6 which connects upon one side by suitable passage 7 with the space or chamber 8 and upon the other side by means of an upwardly extending passage 9 with the chamber 10 above the 80 piston. The annular passage 6 communicates by means of the lateral ports 11 with the chamber 12 in which is designed to reciprocate the pilot valve 13 the annular walls of which control the exit from these 85 ports.

14 is a spring bearing on the upper end of the differential steam piston and disposed within the chamber 10 and acting to assist in holding the said piston in its downward position. This spring, however, is not absolutely essential and it may be omitted without detriment to the successful operation of the valve.

90 15 is a check valve carried by the differential piston and adapted to a seat 16, as clearly shown in Figure 1. As will be readily understood upon reference to Figure 1, the members 5 and 15 are formed separately, the former being cast iron and the latter of some other suitable material such as nickel bronze, the two parts being connected together as one by means of the nut 16' which has threaded engagement with the member 15 and bears against the adjacent 100 end of the member 5, as clearly shown.

105 17 is a spring interposed between the outer end of the nut 16' and the pilot valve 13 and

tending to hold the latter to its seat, although this spring may be omitted without detriment to the successful operation of the device.

5 The seat 16 for the valve member 15 is formed separate and screwed into the opening in the division plate 18, as seen clearly in Figure 1, its flange 19 bearing against a shoulder 20 for an obvious purpose.

10 21 is the stem of the pilot valve. It is guided in the portion 15 and at its lower end guided by a suitable guide 22, in the present instance shown in the form of a bushing held in the nut 23 in the bottom wall 24 of the 15 body portion of the valve.

25 are bolts passed through flanges on the portion 24 of the body of the valve and the upper end of the lower portion 3 for securely holding the same together.

20 The stem 21 of the pilot valve is provided with longitudinal flutes or channels 26 which are always in communication with a counter-bore or chamber 27 in the lower end of the portion 15 of the piston. The pilot valve is adapted to a seat 28 at the lower end of the chamber 12.

30 The depending or skirt portion 29 of the member carrying the seat 16 is provided with a plurality of openings 30 communicating with the chamber 31 beneath the division plate 18, these openings being normally closed by means of a ring 32 carried by the member 15, there being a space 33 surrounding the lower portion of the member 15 and communicating with the chamber 8 when the check valve is unseated and thence communicates with the chamber 31 through the openings 30 beneath the ring 32 when the valve is unseated to produce a gradual opening.

40 34 is a vacuum and pressure piston movable in the chamber formed in the lower portion 3 and having a depending or skirt portion 35 adapted to reciprocate in the chamber 36 formed in the depending portion 3^a, as clearly seen in Figure 1. This depending portion 35 is provided with a plurality of openings 37 adapted to communicate with the atmosphere through openings 38 through the wall of the depending portion 3^a when the piston 34 is raised to bring the openings 37 into communication with the chamber 42.

55 39 is a check valve in the upper end of the chamber 40 formed in the depending portion of the vacuum and pressure piston and adapted to open upward. This valve controls a passage 41 communicating with the space 42 beneath the vacuum and pressure piston in the lower portion 3 of the valve.

60 The passage 41 communicates with the space 43 above the check valve, this space allowing the requisite upward movement of said check valve, as will be hereinafter explained.

44 is a passage or channel formed in the wall of the body portion 1, this channel communicating with an annular space 45 around the nozzle portion 46 which is threaded into the neck 47 extending from the body portion 1 and this annular space 45 has leading therefrom the ports 48 which, in turn, communicate with the annular space 49 surrounding the inner nozzle portion 50 which is also received in the neck 47 and retained in place by the nozzle portion 46. It is to be noted that the annular space 49 communicates with a space 51 between the bores of the nozzle portions 46 and 50.

52 is the outer portion of the nozzle, the same serving also as a jamb nut, being threaded into the neck 47 and bearing against the nozzle portion 46. The bores of the nozzle portions 46 and 52 are inversely tapered, as seen at 53 and 54, respectively, in Figure 1. It will also be noted that the bore of the inner nozzle portion 50 is tapered inversely to the taper 53 of the intermediate nozzle portion 46.

With the parts constructed and arranged substantially as hereinbefore described and with the device in position, in practice the drifting valve is affixed in position and the opening 38 connected with a pipe which is designed to extend below the running board of the engine to take care of the exhaust from the chamber 42 and also to take care of the condensation and to admit air to said chamber through the check valve 39 so as to permit upward movement of the vacuum piston by the pull of the nozzle through the vacuum channel 44. It is to be noted that the vacuum and pressure piston 34 is provided with a comparatively minute equalizing passage 55 say of one-sixteenth inch diameter to equalize the pressure upon both sides of said piston, that is the throttle pressure.

It will also be noted that the depending portion 35 of the said piston 34 is provided with a drain opening 56 say of one thirty-second inch diameter for drainage of water of condensation from the chamber 42.

The operation is as follows:—It is to be understood, of course, that the extension 1^a is connected with the boiler and the extension 1^b connected with the engine, or engines, through the medium of the union members 4 and 4^a, respectively, so that when steam is turned on to the drifting valve, the said steam will enter through the connection 4—1^a into the space 8 above the division portion 18 and through the equalizing hole 7 into the annular channel 6 and thence through the upper equalizing hole 9 into the space 10 upon the upper side of the steam piston and also into the space above the pilot valve, the steam serving to hold the steam piston and the pilot valve firmly against their seats under boiler pressure.

It is to be understood that an engine has

to use some throttle pressure before it has momentum enough to drift; the throttle pressure backs up through the member 4^a and through the nozzle mechanism hereinbefore described and through the vacuum channel 44 into the chamber or space 24 and also into the space 31 below the steam piston and into the chamber 42 below the vacuum and pressure piston 34, all equivalent to throttle pressure, and when the throttle is shut off for the purpose of allowing the engine to drift or move without throttle pressure, the moving pistons of the engine consume the steam in the said spaces or chambers 24 and 31. The throttle pressure in the chamber 42 which is stored beneath the vacuum and pressure piston 34 now expands, by means of the release of the pressure above it, moving the vacuum and pressure piston 34 upward, and at the same time carrying the stem of the pilot valve with it, which causes said pilot valve to move upward uncovering the ports 11, thus allowing of the exhaust of the steam from above the steam piston through the ports 9, annular channel 6 and ports 11, through the flutes in the stem of the pilot valve into the bore 27 and thence into the chamber 31 and out through the nozzle to the engine. This reduces the pressure in the space above the steam piston, making the pressure in the chamber 28 greater than that in the space above the steam piston, thus causing the steam piston to raise from its seat, permitting steam to pass through the chamber 31, through the space 33 and the ports 30, and out through the nozzle to the engine with sufficient velocity to produce a vacuum between the nozzle portions 50 and 46 which acts upon the upper side of the vacuum and pressure piston 34 through the vacuum channel 44, producing sufficient vacuum to hold the drifting valve open until the engine comes to a stop or the throttle is again opened.

The nozzle is so arranged that it will produce from one and one-half to two and one-half inches vacuum through the vacuum channel 44 on the vacuum piston 34 sufficient to exhaust steam under constant pressure to the cylinder or cylinders not exceeding five pounds.

It will be clearly understood that the faster the engine is moving, the freer the opening through the member 4^a and thus there will be delivered a greater quantity of steam to the engine under fast movement than under slow movement, for as the engine begins to come to a stop the pressure in the delivery pipe through the member 4^a will gradually destroy the vacuum that is produced by the two nozzles, which will interrupt the vacuum in the space 24, which causes the vacuum and pressure piston and the steam piston to assume their normal po-

sitions, which closes the valve and the engine stops. The valve remains in this position while the engine is under throttle pressure and also while idle.

From the foregoing it will be clearly understood that this drifting valve produces its own vacuum, operating instantly and preventing any partial formation of vacuum and thus producing a perfect drifting valve which will drift an engine to a complete stop and shut off accurately automatically.

As before stated, the invention is capable of embodiment in a variety of forms. In Figure 2 I have shown one of such modified forms of embodiment, in which the vacuum channel 57 instead of being formed as a passage through the wall of the body portion of the valve is formed of a separate tube held at one end in the bottom wall of the body portion 1 of the valve and its other end expanded or otherwise held in a portion of the nozzle 58. The purpose and function are the same as in the form illustrated in Figure 1.

In the event that the throttle is shut off and then opened suddenly and shut off again so as to destroy the pressure in the chamber 42 beneath the valve 34 and failing to start the valve in operation, then it would be necessary for the engine to create a partial vacuum instantaneously, thus pulling the piston 34 upward, and then the valve 39 serves its purpose of admitting air through the opening 38 into the space 36 and into the chamber 40, lifting the valve 39 and allowing air to flow through the passage 41 into the space 42 to destroy the vacuum produced on the under side of the piston 34.

Modifications in detail may be resorted to without departing from the spirit of the invention or sacrificing any of its advantages.

What is claimed as new is:—

1. In a drifting valve, a steam-controlling valve, a vacuum and pressure piston movable in one direction independent of said steam-controlling valve, means operated by said piston for controlling the movement of said valve, means for operating said steam-controlling valve, pressure means confined in said valve for raising said piston, and a vacuum channel and vacuum-creating means within the valve and affording communication between the space above said piston and the engine for holding said piston in raised position.

2. In a drifting valve, a steam-controlling valve, pressure-operated means movable in one direction independent of said steam-controlling valve for opening the same, a trap for steam beneath said means, and a vacuum channel and vacuum creating means constituting a part of the drifting valve and affording direct communication between the space above the first-named means and the connection with the engine

and operating in conjunction with the flow of steam to the engine to hold said first-named means in raised position.

3. In a drifting valve, the combination 5 with a steam-controlling valve, means for operating the same, and a piston movable in one direction independent of said steam-controlling valve and operable to open position by pressure therebeneath, of a vacuum 10 channel and vacuum-creating means within the valve and affording direct communication between the space above said piston and the connection with the engine for holding said piston in its raised position and 15 means for trapping steam beneath said piston.

4. In a drifting valve, a steam piston, a steam-controlling valve, a vacuum and pressure piston movable in one direction independent 20 of said steam-controlling valve and adapted to be raised by pressure stored therebeneath, and a vacuum channel and vacuum-creating means within the valve and affording communication between the space 25 above said piston and the engine for holding said vacuum and pressure piston in open position, means for trapping steam beneath said piston, and means whereby the steam-controlling valve is operated by the raising 30 of said piston.

5. In a drifting valve, a steam piston, a steam controlling valve, a pilot valve, a vacuum and pressure piston adapted to be raised by pressure stored therebeneath, said 35 pilot valve being controlled by said pressure and vacuum piston, and vacuum-creating means in the valve acting in conjunction with the flow of steam to the engine for holding said vacuum and pressure piston 40 and pilot valve in raised position.

6. A drifting valve embodying a steam-controlling valve, a piston movable in one direction independent of said steam-controlling valve pressure-operated to raised 45 position, means for trapping steam beneath said piston, and a vacuum channel and vacuum-creating means, including a nozzle affording communication between the space above the piston and the engine to supply 50 steam to the engine for lubrication and to create a vacuum above the piston to hold the same in raised position.

7. In a drifting valve, a steam-controlling valve, a steam piston, a pilot valve movable 55 therein, a pressure and vacuum piston movable independently of the steam piston and engageable with the stem of the pilot valve to move the latter, said pressure and vacuum piston being raised by pressure from beneath, and vacuum-creating means within 60 the valve and affording communication between the space above said piston and the engine for holding the same in raised position.

65 8. In a drifting valve, a steam-controlling

valve, a steam piston, a vacuum and pressure piston movable independent thereof by pressure stored therebeneath, a pilot valve movable independently of the steam piston and actuated by movement of the vacuum and pressure piston, a nozzle in the outlet to the engine, and a vacuum channel within the valve affording communication between said nozzle and the space above the vacuum and pressure piston for creating a vacuum 75 to hold the latter in raised position.

9. In a drifting-valve, a steam-controlling valve, a steam piston, a vacuum and pressure piston, a pilot valve movable independently of the steam piston and actuated by 80 the vacuum and pressure piston, means in the valve for creating a vacuum above the vacuum and pressure piston to hold the same in raised position, and means for trapping steam beneath said vacuum and pressure 85 piston to initially raise said piston.

10. In a drifting-valve, a steam-controlling valve, a steam piston, a vacuum and pressure piston, a pilot valve movable independently of the steam piston and actuated 90 by the vacuum and pressure piston, means in the valve for creating a vacuum above the vacuum and pressure piston to hold the same in raised position, means for trapping steam beneath said vacuum and pressure piston to 95 initially raise said piston, and means for admitting atmospheric pressure to the space beneath said vacuum and pressure piston.

11. In a drifting-valve, a steam-controlling valve, a vacuum and pressure piston, 100 a pilot valve movable by said piston, means in the valve for creating a vacuum above the piston and means for trapping steam beneath the same which, by its expansion, actuates said piston at the beginning of the 105 operation of the valve.

12. In a drifting valve, a valve casing having an inlet and an outlet, a check valve controlling the flow of steam therethrough, pistons upon opposite sides of said check 110 valve, the lowermost piston being moved to raised position by pressure stored therebeneath, a nozzle in the said outlet, a pilot valve cooperable with the upper piston and check valve, and a vacuum channel through 115 and within the valve from said nozzle to the space above the lower piston, and means for creating a vacuum above the lower piston to hold the same in raised position.

13. In a drifting valve, a valve casing 120 having an inlet and an outlet, a check valve controlling the flow of steam therethrough, differential pistons upon opposite sides of said check valve, the lowermost piston being moved to raised position by pressure stored 125 therebeneath, a nozzle in the said outlet, a pilot valve cooperable with the upper piston and check valve, a vacuum channel through and within the valve from said nozzle to the space above the lower piston, means for 130

creating a vacuum above the lower piston to hold the same in raised position, and a pressure relief valve operable independently of the upper piston and movable by the 5 lower piston.

14. In a drifting valve, a valve casing having an inlet and an outlet, a check valve controlling the flow of steam therethrough, differential pistons upon opposite sides of 10 said check valve, the lowermost piston being moved to raised position by pressure stored therebeneath, a nozzle in the said outlet, a pilot valve cooperable with the upper piston and check valve, a vacuum channel through 15 and within the valve from said nozzle to the space above the lower piston, vacuum creating means, and a check valve in the lower piston, the lower piston being raised by pressure stored therebeneath and held in 20 raised position by the vacuum created through said channel.

15. In a drifting valve, a valve casing having an inlet and an outlet, a check valve controlling the flow of steam therethrough, differential pistons upon opposite sides of 25 said check valve, a nozzle in the outlet, a pilot valve cooperable with the upper piston and check valve, a vacuum channel from said nozzle to the space above the lower piston, a pressure relief valve operating independently of the upper piston and movable by the lower piston, and a check valve in 30 the lower piston, the lower piston being raised by pressure stored therebeneath and held in 35 raised position by the vacuum created through said channel.

16. In a drifting valve, steam-controlling

means, combined with pressure means movable in one direction independent of said steam-controlling means acting to move the 40 same in one position, and a vacuum channel and vacuum-creating means within the valve body independent of said pressure means and affording direct communication between the space above said pressure means and the 45 connection to the engine for holding said pressure means in such position and means for trapping steam beneath said piston.

17. In a drifting valve, a pilot valve, a 50 vacuum and pressure piston movable independent of said pilot valve for a portion of its upward travel, a steam piston independent thereof, a pressure-relieving means, and means for opening the latter by expansion of steam beneath the vacuum and pressure 55 piston and vacuum creating means within the valve casing independent of the first-named piston and affording direct communication between the pipe leading to the engine and the space above said piston to hold 60 the latter in raised position.

18. In a drifting valve, a steam controlling valve, a vacuum and pressure piston, pressure means for raising the latter, means whereby the expansion of steam initially 65 raises said piston, and vacuum-creating means embodying a passage through the casing of the valve independent of said piston and affording direct communication between the piston chamber and the pipe leading 70 to the engine.

In testimony whereof I affix my signature.

VINCEN P. McVOY.
